UNITED STATES PATENT OFFICE.

WALFRID LARSON, OF KINGSBURG, CALIFORNIA.

TIRE-BOLT WRENCH.

SPECIFICATION forming part of Letters Patent No. 623,793, dated April 25, 1899.

Application filed October 22, 1898. Serial No. 694,296. (No model.)

To all whom it may concern:

Be it known that I, WALFRID LARSON, of Kingsburg, in the county of Fresno and State of California, have invented a new and Improved Tire-Bolt Wrench, of which the following is a full, clear, and exact description.

My invention relates to an improvement in devices to be used for tightening and loosening nuts upon bolts, and particularly nuts upon tire-bolts.

The invention consists of the novel features of construction and combinations of parts, as hereinafter described, and pointed out in the appended claims.

Reference is to be had to the accompanying drawings, forming a part of this specification, in which similar characters of reference indicate corresponding parts in all the figures.

Figure 1 is a plan and partial section of the wrench. Fig. 2 is a view of the same at right angles to that shown in Fig. 1, and Fig. 3 is a detail view of a spring employed in connection with the wrench.

My device is intended for use in connection with such work as the tightening and removing of tire-bolts where one end of the bolt may be engaged by one jaw of a pair of tongs to prevent the nut from rotating and the nut at the opposite end may be engaged by a wrench which may be rotated, so as to loosen or tighten the nut.

The device is mounted upon two levers A and B, which are pivoted to each other, so as to form a pair of tongs. One of these levers A has a single jaw A', through the outer end of which is threaded a bolt H, the said bolt being provided at one end with a thumb-piece or flattened wing by which it may be turned and at the other end with a flattened point h, similar to the end of a screw-driver, by which the end of the bolt may be engaged to prevent its turning. The jaw A', as well as the complementary jaws upon the lever B, is made of such a size as to embrace the rim 45 of the wheel and permit of the bolt H engaging with the tire-bolt. The lever B has jaws which are formed in two parts B' and B², separated from each other and having a recess b, within which are mounted two intermeshing pinions D and D'. The pinion D is secured upon a shaft E, which passes

through both jaws B' and B² and also through a slot a in the jaw A', the slot being designed to accommodate the shaft as the levers are swung upon their pivot. This shaft is provided with a crank F, so that it may be rotated, said crank having a bend F', by which it may conveniently pass the bolt H, and a handle I, the handle being secured by means of a nut I' upon its inner end, the bolt of the handle I passing through a slot f' in the outer end of the crank. By this means the position of the handle I may be adjusted.

The pinion D' is mounted upon a tube G by means of a keyway and a feather d, so that the tube may slide in but must rotate with the pinion. The keyway or slot stops short of the outer end of the tube G, thus forming a stop which engages the outer end of the key or feather d, so as to prevent the two being forced too far inward or from accidentally falling out of the pinion. The inner end of the tube G is provided with a beveled outer surface G', which may be forced into the wheel-rim, if necessary. This end of the tube may be provided with flat surfaces corresponding in number with the sides of the nut which the tube is to fit, and the position of the nut may then be told at any time. The central bore G² of the tube is shaped to correspond with the shape of the nut to be operated upon and is slightly tapered, the smaller end being that which is used as a wrench. The tube is free to turn in the jaws B' and B² and serves as a shaft for the pinion D'. The opposite or outer end of the tube G is reduced in size, as shown at G³, to receive the end of a spring C. This spring is formed as a flat bar and is secured at one end to the jaw B² by means of a clamping-screw 90 C' and has its opposite end formed as a ring C², adapted to surround the reduced portion G³ of the tube G and to engage the shoulder at the inner end of said reduced portion. The spring is slightly bent, as clearly shown 95 in Fig. 1, so that the tension thereof may be readily adjusted by turning the bolt C', which for convenience is provided with a flat head or thumb-piece.

Upon the jaw B² is secured a receptacle J, 100 adapted to receive the nut after it has been removed from the bolt. This receptacle is

secured to the jaw B² by means of a screw J', which passes through a slot in one side of the receptacle and secures the latter in place, and the receptacle is provided with a notch to receive the reduced portion G³ of the tube G. The nut when removed from the bolt passes through the tube G and drops into the receptacle J.

In using my device the jaws are made to embrace the rim of the wheel, and the bolt II is screwed down upon the head of the bolt, the end of the socket-tube G being previously passed over the nut. On tightening the bolt II the pressure comes upon the jaw B' and not upon the tube G. By reason of this the pressure upon the bolt may be made greater than would be possible if the end of the tube G were relied upon for sustaining the back pressure. The tube G is held upon the nut by means of the spring C. By reason of this construction the tube G is not forced into the wood more than is necessary to securely hold the nut, and marring of the wheel-rim is thus avoided.

Having thus described my invention, I claim as new and desire to secure by Letters Patent—

1. A tire-bolt wrench, comprising two pivoted levers forming a pair of tongs, a socket-tube mounted to turn and slide in one jaw, 30 means for turning the socket-tube, a flat spring secured to the outer side of the jaw and engaging the end of the socket-tube to hold it upon the nut, and an adjusting-bolt passing through the spring by which its tension may be adjusted.

2. A tire-bolt wrench, comprising two pivoted levers forming a pair of tongs, a socket-tube mounted to turn and slide in one jaw, a spring engaging said tube to hold it in engagement with the nut, a tension-adjusting screw for the spring, means for turning the socket-tube, an adjustable device carried by the other jaw of the tongs and engaging the bolt-head to hold it against rotation, and a 45 cup or receptacle having its upper end placed to receive the nut from the rear end of the tube.

3. A tire-bolt wrench, comprising two pivoted levers forming a pair of tongs, a socket-tube mounted to turn and slide in one jaw, 50 a pinion having rotative connection with the socket-tube, an intermeshing pinion having a crank connected therewith, a flat spring secured lengthwise the outer side of the jaw and engaging the socket tube, to hold it upon the nut and a bolt passing through the spring and into the jaw whereby the tension of the 55 spring may be readily adjusted.

4. A tire-bolt wrench, comprising two pivoted levers forming a pair of tongs, one jaw having a pinion-receiving recess, two intermeshing pinions within said recess, a crank and shaft connected with one pinion, a socket-tube forming the shaft of the other pinion and connected to rotate with the pinion and 60 to slide in the jaw and pinion, a spring engaging the rear end of the socket-tube and a

thumb-nut for adjusting the tension of said spring.

5. A tire-bolt wrench, comprising two pivoted levers forming a pair of tongs, the jaw end of one lever having gears journaled therein, and one of the gears carrying a socket-wrench, the other gear having a shaft extending through the opposite jaw, a crank upon this shaft outside of the last jaw, said jaw having a slot or hole loosely accommodating the shaft and also having a bolt-head-engaging member, substantially as described.

6. A tire-bolt wrench, comprising two pivoted levers forming a pair of tongs, the jaw end of one lever having gears journaled therein and one of the gears carrying a socket-wrench, the other gear having a shaft extending through the opposite jaw, a crank upon this shaft outside of the last jaw, said jaw having a slot or hole loosely accommodating the shaft and also having a threaded bolt passing through its end and adapted to engage the bolt-head, substantially as described.

7. A tire-bolt wrench, comprising two pivoted levers forming a pair of tongs, the jaw end of one lever having gears journaled therein, and one of the gears having a hollow shaft keyed to turn with the gear and slidable lengthwise therein, said shaft forming a nut-engaging socket, the other gear having a shaft extending through the opposite jaw, a crank upon this shaft outside of the last jaw, said last jaw having a slot or hole loosely accommodating the shaft, and also having a bolt-head-engaging member, substantially as described.

8. A tire-bolt wrench, comprising two pivoted levers forming a pair of tongs, the jaw end of one lever having gears journaled therein, and one of the gears having a hollow shaft keyed to turn with the gear and slidable lengthwise therein, said shaft forming a nut-engaging socket, a spring engaging the socket-shaft to yieldingly hold it inward, the other gear having a shaft extending through the opposite jaw, a crank upon this shaft outside of the last jaw, said last jaw having a slot or hole loosely accommodating the shaft and also having a bolt-head-engaging member, substantially as described.

9. A tire-bolt wrench, comprising two pivoted levers forming a pair of tongs, two pinions journaled in one jaw of the tongs, means for turning the pinions, one pinion having a hollow shaft forming a nut-engaging socket and provided with a key-and-feather connection with this pinion, the key-receiving slot in the shaft stopping short of its outer end and thus forming a stop to prevent the shaft from passing through the pinion in one direction, and a spring engaging the outer end of the shaft to hold it inward, substantially as described.
